AMMUNITION HOIST

Ralph L. Tweedale, Waterbury, Conn., assignor to
 The Waterbury Tool Company, Waterbury,
 Conn., a corporation of Connecticut

Application October 3, 1936, Serial No. 103,899
 Renewed October 28, 1939

17 Claims. (Cl. 89—46)

1

This invention relates to power transmissions and more particularly to a conveyor for delivering articles from one station to another wherein a fire hazard is present at one station and in which it is desired to prevent the possibility of flame transmission between the two stations at all times, while permitting the continued passage of articles between the stations. The invention is particularly adapted to delivering ammunition aboard ship from an ammunition storage compartment to a position at the guns for use therein, although it will be understood that the invention may be adapted to other uses wherein similar conditions and problems are encountered.

It is customary in war vessels to locate the ammunition magazines or storage chambers in the lower part of the ship where the possibility of their contents being exploded by enemy projectiles is most remote. The guns which use the ammunition being situated on the upper decks of the ship, either in turrets or on deck mountings, it is necessary to provide means for conveying ammunition from the magazine to a position near the guns where it may be readily placed in the guns as needed.

Various types of conveyors have been heretofore provided for this purpose and where high rates of delivery to rapid firing guns are required, the so-called dredger type ammunition hoists have marked advantages over other types in use. Such a hoist usually comprises an endless chain conveyor which is encased in a continuous tubular hoist trunk or casing extending through the ship from the loading station in or adjacent the magazine to the unloading station adjacent the gun. This continuous hoist trunk provides a conduit which introduces the possibility of flame transmission to the magazine whenever accidental explosions occur at the gun or whenever an enemy projectile explodes in or near the hoist trunk.

In order to break this continuous path for flame travel to the magazine, it has been found necessary heretofore to deliver the ammunition in two stages by two entirely independent ammunition hoists with a transfer station where the ammunition is carried manually from the delivery end of the lower hoist to the loading end of the upper hoist. This construction, while satisfactory from the standpoint of safety of the installation and effectiveness to prevent the transmission of flare-backs to the magazine, adds considerably to the weight and cost of the installation since each of the two sections of the hoist

2

must be provided with its own independent drive mechanism. Furthermore additional crew is required for handling ammunition at the transfer station, which not only increases the number of men required for each gun to be fired but presents also a retarding element in the delivery of ammunition since it introduces one more place for unavoidable human errors and delays to interfere with the intended operation of the hoist.

10 It is an object of the present invention to provide a conveyor system particularly adapted to rapid delivery of ammunition between a loading station adjacent the magazine and an unloading station adjacent the gun by which ammunition 15 may be delivered through two conveyors in end to end relation together with automatically operating transfer means for transferring ammunition between the conveyors.

16 It is a further object to provide such a conveyor system in which ammunition may be automatically transferred between the two conveyors while maintaining a flame-proof wall between the two ends of the conveyor system.

17 A further object is to provide a conveyor system 20 incorporating a transfer mechanism wherein a rotary cylinder is provided for transferring articles between the conveyors and to provide suitable automatic drive mechanism for operating the conveyors and the transfer mechanism 25 in timed relation.

18 It is also an object to provide a conveyor system of the type described wherein a control mechanism for the two conveyor drive mechanisms is responsive to the presence or absence 30 of an article at the ends of the conveyors.

19 Further objects and advantages of the present invention will be apparent from the following description, reference being had to the accompanying drawings wherein a preferred form of the present invention is clearly shown.

20 In the drawings:
 Fig. 1 is a diagrammatic cross section of a ship embodying a preferred form of the present invention.

25 Fig. 2 is a circuit diagram showing the hydraulic circuits incorporated in the driving and control mechanism of the present invention.

30 Fig. 3 is a side view partly in section of a transfer station incorporating the present invention.

35 Fig. 4 is a vertical cross section through the transfer station.

40 Fig. 5 is a horizontal cross section on line 5—5 55 of Fig. 3.

Fig. 6 is a view corresponding to Fig. 3 showing the opposite side of the mechanism.

Fig. 7 is a cross section on line 7—7 of Fig. 3.

Fig. 8 is a cross section on line 8—8 of Fig. 3.

Fig. 9 is an electrical circuit diagram showing the interlock control mechanism.

Referring now to Fig. 1 there is indicated diagrammatically a portion of a longitudinal section of a war vessel having superimposed decks 10 and 12 of usual construction, the deck 12 being constructed of armor plate. The spaces between the decks are divided into suitable compartments by partitions 14 in any suitable fashion. Indicated at 16 is a deck gun adjacent which is mounted the delivery end 18 of a conveyor system 20 extending between the gun 16 and a compartment 24 which may be either a magazine compartment for the storage of ammunition or a handling room adjacent such a compartment. Within the compartment 24 is located a loading station 26 of any suitable construction forming the lower terminus of the conveyor 20. The conveyor system 20 comprises two dredger type ammunition hoist sections 28 and 30 arranged in end to end relation at a transfer station 32. The transfer station 32 is located immediately below the armor deck and includes driving and control mechanism for operating both the hoist sections 28 and 30 and the transfer mechanism inside the transfer station 32.

Referring now to Figs. 2 through 9 wherein the construction of the transfer station 32 is illustrated in detail, there is shown a casing 34 forming the lower end of the hoist section 28 and the upper end of the hoist section 30 to which the casing 34 may be tightly sealed at the flanges 36 and 38. The casing 34 serves not only to enclose the drive sprockets 40 and 42 and the hoist chains or conveyor bands 44 and 46 to which are attached carrying lugs 48 and 50, but also as a mounting for the hoist driving and control mechanism. The latter may be of any suitable construction. The drive mechanism illustrated and control therefore comprises a fluid motor 52 adapted to drive the sprockets 40 and 42 through worm drives 54 and 56, the latter being connected in driving relation by gearing 57 and shaft 59. A variable displacement pump 58 (see Fig. 2) and an auxiliary pump 60 are driven by an electric motor 62 to supply fluid to the motor 52 through a control unit 64. The control unit 64 is constructed to control the displacement of the pump 58 and to control communication between the pump 58 and the motor 52 through conduits 66 in a manner to provide for automatically moving the hoist chains 44 and 46 through one flight whenever a starting "shot" of fluid from the auxiliary pump 60 is admitted to the device 64 through a control conduit 68.

For this purpose the control unit 64 comprises a body 41 having a cylindrical bore 43 in which is mounted a spool valve 45 for the purpose of blocking or opening the passage of oil between the conduits 66 and conduits 67. A second cylindrical chamber 49 carries a spool valve 51 for the purpose of reversing the flow between the conduits 47 and a pair of conduits 53 which lead to the fluid motor 52. The body 41 also has at its upper end a bore 55 in which is mounted a spool valve 56' for controlling the stroke regulating fluid motor of the pump 58. A conduit 58' extends from the auxiliary pump 60 to the upper end of the bore 55 while a conduit 61 enters the bore 55 at its mid-portion. The valve 56' is adapted to selectively control and reverse the

connections of the conduits 58' and 61 with a pair of conduits 63 and 65 leading to opposite ends of the stroke regulating mechanism at the pump 58. The valves 45 and 56' are formed integrally upon a common stem having an enlarged portion 67 around which is slidably mounted a lift piston 69. The latter has a cylindrical upper portion 71 slidably fitted in a chamber 73 which communicates with the upper end of the bore 55 through a passage 75 formed in the spool of valve 56'. The piston 69 has a portion 77 of larger diameter than the portion 71 and slidably fitted in a chamber 79 to which the conduit 68 leads. The bottom wall of the piston 69 is provided with an opening 81 forming a clear passage around the stem of valve 45 and having a seat on which the enlarged portion 67 of the stem is adapted to rest for the purpose of closing this passage. The space inside the piston 77 communicates with the tank through a passage 81 formed in the stem of the valve 45. At its lower end the valve stem has a roller 83 acting as a follower for a cam 85. The latter is connected by a suitable drive means not shown to the shaft of the sprockets 40 so that the cam 85 makes one revolution while the chains 44 and 46 travel through one flight distance. The cam 85 has a depression in which the roller 83 is shown at rest. In this position the valve 45 is completely closed while the valve 56' connects the conduit 63 to the pressure line 58' and the conduit 65 to the tank line 64. To either side of this depression are elevated portions 87 which hold the valves in such a position that the valve 45 is opened to a considerable degree while the valve 56' still connects conduit 63 with conduit 58' and conduit 65 with conduit 61. The remainder of the periphery of the cam 85 is raised still further so as to completely open the valve 45 and to reverse the connections at the valve 56'. When the valves are raised to this upper extreme position the valve stem has been lifted higher than it is possible to lift the piston 69, so that the enlarged portion 67 lifts away from the seat in the bottom wall of the piston 69. The cam 85 and its drive mechanism are enclosed in a suitable oil-tight housing not shown, the interior of which is connected to tank. The entire arrangement of the control unit 64 is such that whenever a shot of oil is admitted through the conduit 68 to the chamber 79, the piston 69 is lifted due to the enlarged portion 67 being on its seat in the bottom wall of the piston 69. The piston 69 and both valves 45 and 56' are accordingly lifted to a position just short of the highest position to which the cam would lift them. Thus the valve 45 is opened and the valve 56' is reversed to cause the stroke of the pump 58 to be increased at a rate determined by the volumetric capacity of the auxiliary pump 60. Oil is delivered to and returned from the fluid motor 52 through the conduits 66, 47, and 53, thus causing the motor 52 to operate, turning the cam 85. The latter will contact the roller 83 after about one-quarter of a revolution when the highest part of the cam strikes the roller 83, thus lifting the valves 45 and 56' a further amount. This additional lift raises the enlarged portion 67 off from the seat in the bottom wall of the piston 69, thus permitting the oil trapped in the chamber 79 to escape through the opening in the bottom wall of the piston 69 and through the passage 81 to tank. As soon as the cam has completed an approximate one-half revolution in addition, the roller 83 drops down to the cam portion 87, thus reversing connections at valve 56'.

but not completely closing the valve 45. The stroke of the pump 58 is thus reduced at a rate determined by the capacity of pump 60 causing the motor 52 to decelerate. When the cam 85 has completed a revolution, the roller 83 returns to the position shown in the drawings, completely closing the valve 45. At this time the enlarged portion 67 again comes to rest on its seat in the bottom wall of piston 69, thus placing the apparatus in condition for restarting whenever another shot of oil is introduced to the conduit 68. It will be noted that should a shot of oil be introduced to the conduit 68 before the cam 85 has made one revolution, the lift piston 69 will not rise because a free path is opened from the chamber 79 to tank through the passage in which the enlarged portion 67 seats. It will also be noted that oil pressure from the auxiliary pump is constantly exerted over the upper end of the valve 56 creating a bias for the entire stem assembly in the downward direction. Likewise this pressure is exerted over the annular area at the top of the portion 71 of the lift piston 69 biasing the latter downwardly whenever pressure is relieved in the chamber 79 by the opening of the passage through the bottom wall of the piston 69.

The casing 34 is provided on its front face above the sprockets 42 with an extension 70 having an opening 72 of proper size and shape to permit a piece of ammunition to pass therethrough. The extension 70 is hinged to the casing 34 at 74 along one edge thereof and is adapted to be clamped in sealing engagement therewith by suitable securing means 76. The extension 70 is formed with a cylindrical recess 78 within which is mounted a transfer cylinder 80. The cylinder 80 is pivoted on bearings 82 at the top and bottom ends thereof, the upper bearing being mounted in a removable cap member 84 rigidly secured to the extension 70. The cylinder 80 is provided with recesses 86 and 88 of suitable shape to receive a piece of ammunition within the confines of the cylinder so that the latter may rotate between the position illustrated and a position 180° away in which the recess 86 is in register with the opening 72 and the recess 88 is opposite the chain 44.

The lower end of the cylinder 80 has secured thereto a shaft 90 which carries a pinion 92 for driving the shaft 90 through a slip clutch mechanism 94. The latter mechanism is of any suitable type arranged to yield upon the application of excessive torque and to have two positions 180° apart in which the clutch is effective to drive the shaft 90. The pinion 92 engages with a segmental gear 96 formed on arm 98 pivoted at 100 at the bottom of the extension 70. The pivot 100 is embraced by flange portions 102 (Fig. 8) of a closure member 104 which is secured to the bottom of the extension 70 by bolts 106 and which closes an opening 108 formed in the casing 34 above the sprockets 42. The opening 108 is of suitable size and shape to permit the pinion 92 and clutch mechanism 94 as well as the arm 98 to pass therethrough when the extension 70 is swung away from the casing 34 on its hinges 74. Outside the casing the arm 98 carries a depending pin 110 adapted to seat in a groove 112 formed on a cam 114. The cam 114 is rotatable on a shaft 116 secured in a boss 118 on the extension 70 in line with the pivots of the hinges 74. The cam 114 has secured thereto a bevel gear 120 and a pair of wing cams 122 and 124. A bevel pinion 126 is keyed to a shaft 128 projecting into the casing of the worm drive 54 on the interior

of which the shaft 128 carries a bevel gear 130 meshing with a bevel gear 132. The latter is secured to a spur gear 134 meshing with a spur gear 136 secured to a shaft 138 for the sprockets 40.

Pivotedly mounted in the casing 34 adjacent the extension 70 are a pair of barriers or flapper doors 140 adapted to rest against the surface of the cylinder 80. The doors 140 are of sufficient width to prevent ammunition from accidentally falling from the recesses 86 or 88 on to the conveyor chain 44 when the doors are in the position illustrated. The doors 140 are secured to pivot shafts 142 which extend below the bottom of the extension 70 and carry arms 144 connected by a cross shaft 146 for simultaneous operation. One of the shafts 142 extends below the bulged portion 147 of the casing 34 and projects outside thereof, and carries secured to its lower end a trip arm 148 extending into the path of the wing cam 122 whereby the latter may swing the doors 140 open at certain times. Spring means, not shown, are provided for normally maintaining the flapper doors in the position illustrated. The other pivot shaft 142 (Figure 4) carries at its lower end and within a bulged portion 149 of casing 34 a cam 150 adapted to actuate through a roller follower 152, a lever 154 pivoted in the casing 34 at 156. Outside the casing the lever 154 is connected to actuate a stem 158 of a flapper door interlock valve 160 (see Fig. 2) whenever the flapper doors 140 are open.

Pivotedly mounted in the casing 34 above the sprockets 42 is an ejector arm 162 which carries at its outer end a latch 164 adapted to permit a piece of ammunition such as 166 to move upwardly past the arm 162 when the arm is in the position shown in Fig. 4. The arm 162 is secured to a shaft 168 (Figure 7) which carries at its outward end a depending trip lever 170 adapted to be actuated by the wing cam 124. A stop pin 172 limits the downward movement of the arm 162. The portion of the casing 34 which surrounds the sprockets 42 is formed with an opening 174 in the top thereof through which ammunition is delivered by the carrier lugs 50. Stationary guide members 176 are formed adjacent the opening 174 on either side of the path of the ejector arm 162 for guiding ammunition into the opening 174. A removable cover member 178 is secured to the extension 70 and to the casing 34 when the former is secured in the position shown in the drawings. A pair of pivoted latches 180 (Fig. 3) are secured in the cover 178 adjacent the opening 174 to retain ammunition which is delivered through the opening 174 and prevent its return therethrough.

Pivotedly secured in the casing 34 below the opening 174 is an upper trip member 182 for the lower hoist section 30 which is connected through a shaft 184, lever 186, link 188 and lever 190 to a cam 192 adapted to actuate an interlock valve 194 (see Fig. 2). Pivotedly mounted in the casing 34 at 196 is a lower trip 198 for the upper hoist section 28 which is adapted to actuate through a lever 200, an interlock valve 202. The lever 200 may also be actuated manually by the handle portion thereof if necessary. The lower trip 198 is adapted to be depressed by a piece of ammunition such as 204 when it is placed in position on the hoist chain 44. A solenoid operated interlock valve 206 is mounted together with the interlock valves 160, 194, and 202 in an interlock valve body 208. The valve 202 is adapted to connect a conduit 210 with a conduit 212 whenever

the lower trip 198 is depressed and to connect a conduit 214 with a conduit 216 whenever the trip 198 is raised by the removal of a piece of ammunition therefrom. The valve 194 is arranged to connect the conduit 212 with a conduit 218 whenever the upper trip 182 is released by the removal of ammunition from the upper end of the lower hoist section 30 and to connect conduits 216 and 218 when a piece of ammunition lies under the trip 182. The valve 206 is adapted to connect 10 conduit 218 and a conduit 220 whenever a solenoid 222 is energized and to block communication therebetween when the solenoid is deenergized. The valve 160 is adapted to open communication between the conduit 220 and conduit 68 whenever the flapper doors 140 are closed and to interrupt communication when the flapper doors are open.

The solenoid 222 is under the control of an upper trip 224 for the upper hoist 28, a lower trip 226 for the lower hoist 30 and a flapper door cam 228 at the loading station 26 as well as a reverse lever 230. For this purpose the upper trip 224 actuates a three-way switch 232; the lower trip 226 actuates a three-way switch 234; the cam 228 actuates a make and break switch 236; and the reverse lever 230 actuates a pair of three-way switches 238 and 240. The lever 230 also actuates a reverse interlock valve 242 for connecting a conduit 244 leading from the auxiliary pump 60 either to the conduit 210 or the conduit 214. The main reverse valve 51 within the control unit 64 is also simultaneously controlled by the reverse lever 230 whereby the connection between the pump 58 and the fluid motor 52 may be reversed 35 for operating the hoist to lower ammunition.

Referring now to Fig. 9 the electrical circuit for the switch system which operates the solenoid 222 is illustrated. The position of the various switches illustrated in Fig. 9 corresponds to the 40 position of their operating parts illustrated in Fig. 2. From this it will be seen that with the reverse lever 230 in position for hoisting ammunition as shown in Fig. 2, the solenoid 222 is energized only when the flapper doors 228 are closed, the lower trip 226 is depressed by a piece of ammunition, and the upper trip 224 is released by the removal of ammunition from the delivery end 18. With the reverse lever 230 in the lowering 45 position the solenoid 222 is energized only when the lower flapper doors are closed, when there is no ammunition on the lower trip 226, and when a piece of ammunition has been placed in the delivery end 18 to deflect the upper trip 224. The complete electric and hydraulic interlock system is thus effective, when the reverse lever 230 is set for hoisting, to admit fluid from the auxiliary pump 60 to the control unit 64 through conduit 68 only when both the flapper doors 140 and the flapper doors at the loading station 26 are closed, when there is no ammunition in the delivery end of both hoist sections 28 and 30, and when there is a piece of ammunition in place on the lower trips 198 and 226. Only when all of these conditions have been fulfilled 50 will an impulse of pressure fluid be supplied to the control unit 64 for starting the conveyor drive mechanism to operate. When the reverse lever 230 is moved to lowering position, the reverse switches 238 and 240 reverse the response of the upper trip 224 and the lower trip 226 while the interlock reverse valve 242 reverses the response of the lower trip 198 and the upper trip 182. Thus, it will be seen that for either direction of operation of the hoist, it is necessary that for each hoist 55

there must be a piece of ammunition present at the end which is used for loading and no ammunition present at the end to which it is delivered.

In operation with the motor 62 and the pumps 58 and 60 running and with the hoist at rest due to the presence of a piece of ammunition at the delivery station 18, trip 224 keeps the solenoid 222 deenergized so that pressure fluid from the pump 60 is blocked off from the conduit 68 at the valve 206. Assuming a piece of ammunition to lie on the lower trip 198 and a piece of ammunition to rest in the recess 88 and that a piece of ammunition has been manually loaded at the loading station 26 to rest on the trip 226 and the ammunition removed from the delivery end 18, fluid pressure will be admitted to conduit 68 and the motor 62 will drive the hoist chains 44 and 46. As soon as the chains 44 and 46 start to move the cams 114, 122 and 124 are caused to rotate by the gearing 120, 126, 130, 132, 134, and 136 and shaft 128. The gear ratio between shaft 138 and cam 114 is such as to produce one half a revolution of the cam 114 while the hoist chains 44 and 46 move through the distance of one flight.

During the initial movement of the chains the cam 114 moves through a dwell portion. Thereafter the cam 114 moves the arm 98 and pin 110 to actuate the pinion 92 and cylinder 80 through half a revolution. The direction of rotation of the cylinder 80 is reversed on alternate hoist cycles; that is, during one flight movement, the cylinder 80 may rotate clockwise while during the next flight movement it will rotate counter-clockwise. Considerably before the end of a flight, the cam 114 moves to a second dwell portion and thereafter the cam 122 actuates the trip arm 148 to open the flapper doors 140 and simultaneously the cam 124 actuates the arm 170 to lift the ejector arm 162. The spacing between the adjacent lugs 50 is such as to provide some overtravel of the lug 50 past the position shown in Fig. 4 before the next lug 50 comes into position under the lower trip 226. The cams 122 and 124 operate during this additional movement at the end of a cycle and transfer the ammunition delivered by the hoist section 30 to the recess 88 and transfer the ammunition in the recess 86 to position on the lower trip 198. Thereafter as soon as the piece of ammunition delivered to the delivery station 18 is removed and another piece of ammunition is placed in the loading station 26, the hoist again operates through one cycle, the same as before.

If at any time during the operation of the hoist an accidental explosion should occur adjacent the gun or in the trunk of the hoist section 28 due to a hit by an enemy shell, the transmission of flare-backs or flame travel of any kind to the compartment 24 is effectively prevented at the transfer station 22. It will be noted that no matter what position of the cylinder 80, there is no path for flame to travel from the trunk of the hoist section 28 to the trunk of the hoist section 30. The cylinder 80 forms a seal at the opening 72 by its engagement with the recess 78 and any gas pressure existing in the trunk of the hoist section 28 above the pressure in the trunk of the hoist section 30 tends to force the cylinder 80 into tighter engagement with the walls of opening 72. The arc of contact of the recess 78 with the cylinder 80 is substantially greater than the arc subtended by the recesses 86 and 88. By this construction it is insured that the opening through which ammunition is

transferred from the hoist section 30 to the hoist section 28 is maintained sealed at all times.

For lowering ammunition the casing 178 is removed and the extension 70 and the mechanism carried thereby is unfastened at the fastenings 76 and swung outwardly from the upper section of the casing 34. This exposes the flapper doors 140 as well as the opening 174 so that ammunition may be manually transferred from the hoist section 28 to the hoist section 30. During lowering operation the flapper doors 140 and those at the loading station 26 may be latched open by detent mechanism, not shown, for removing ammunition from the lower trips 198 and 226. During lowering operation the interlock system operates in the manner previously described to initiate operation of the hoist drive mechanism only when ammunition has been placed in the upper ends of both hoist sections and has been removed from the lower ends thereof. The hoist may also be operated to raise ammunition should an accident befall the automatic transfer mechanism by swinging it outwardly as described for lowering operation since the action of the interlock system is independent of the position of the extension 70.

During operation with manual transfer during either lowering or hoisting the ejector arm 162 is preferably rendered inoperative by manually raising the same upwardly and inserting a holding pin through a hole 246 in the casing 34. A projection 248 adjacent the guide 176 abuts a recess 250 on the latch 164 when the ejector arm 162 is raised sufficiently to permit the holding pin to be inserted underneath it through the hole 246. The lug 248 thus retracts the latch 164 from the path of the ammunition into and out of the hole 174. During operation with manual transfer while hoisting suitable detents 252 which are normally held in ineffective position by a handle retaining mechanism 253 may be rendered effective to prevent the fall of ammunition from raised position whenever the lug 50 passes beyond the position illustrated in Fig. 4.

When initially filling the hoist with pieces of ammunition if the latter has been completely emptied, it will be noted that the lower trip lever 198 will not be depressed during the first few cycles because there will be no piece of ammunition placed thereon until the lower hoist 46 has been completely filled from top to bottom. Under these conditions the lever 200 (Figure 6) may be manually operated to simulate the presence of ammunition on the trip 198 and a cycle initiated in this manner. As soon as the first piece of ammunition reaches the transfer mechanism and is deposited on the trip 198, further manual operation thereof is unnecessary.

While the form of embodiment of the invention as herein disclosed, constitutes a preferred form, it is to be understood that other forms might be adopted, all coming within the scope of the claims which follow.

What is claimed is as follows:

1. In a conveyor system for delivering ammunition between a loading station adjacent a storage compartment and a station for use the combination of a first endless band conveyor having a delivery end adjacent the station for use, a second endless band conveyor having a loading end at the loading station, said conveyors being arranged in substantially end to end relation, a flame-proof casing surrounding the first conveyor and transfer means for transferring ammunition from the second conveyor to the first conveyor comprising a rotatable cylinder having an ammu-

nition receiving recess arranged to receive a piece of ammunition from the second conveyor and upon rotation through a predetermined angle about an axis generally parallel to line of movement of the conveyors to deliver the piece of ammunition to the first conveyor.

2. In a conveyor system for delivering ammunition between a loading station adjacent a storage compartment and a station for use the combination of a first endless band conveyor having a delivery end adjacent the station for use, a second endless band conveyor having a loading end at the loading station, said conveyors being arranged in substantially end to end relation, a flame-proof casing surrounding the first conveyor and transfer means for transferring ammunition from the second conveyor to the first conveyor comprising a rotatable cylinder having an ammunition receiving recess arranged to receive a piece of ammunition from the second conveyor and upon rotation through a predetermined angle about an axis generally parallel to line of movement of the conveyors to deliver the piece of ammunition to the first conveyor, said cylinder cooperating with said casing to maintain a flame-proof seal between the loading station and the station for use at all times.

3. In a conveyor system for delivering ammunition between a loading station adjacent a storage compartment and a station for use the combination of a first endless band conveyor having a delivery end adjacent the station for use, a second endless band conveyor having a loading end at the loading station, said conveyors being arranged in substantially end to end relation, a flame-proof casing surrounding the first conveyor, transfer means for transferring ammunition from the second conveyor to the first conveyor comprising a rotatable cylinder having an ammunition receiving recess arranged to receive a piece of ammunition from the second conveyor and upon rotation through a predetermined angle about an axis generally parallel to line of movement of the conveyors to deliver the piece of ammunition to the first conveyor, and ejector means for moving ammunition from the second conveyor toward the ammunition receiving recess.

4. In a conveyor system for delivering ammunition between a loading station adjacent a storage compartment and a station for use the combination of a first endless band conveyor having a delivery end adjacent the station for use, a second endless band conveyor having a loading end at the loading station, said conveyors being arranged in substantially end to end relation, a flame-proof casing surrounding the first conveyor, transfer means for transferring ammunition from the second conveyor to the first conveyor comprising a rotatable cylinder having an ammunition receiving recess arranged to receive a piece of ammunition from the second conveyor and upon rotation through a predetermined angle about an axis generally parallel to line of movement of the conveyors to deliver the piece of ammunition to the first conveyor, ejector means for moving ammunition from the second conveyor toward the ammunition receiving recess, and means for operating said ejector means in timed relation to the operation of a conveyor.

5. In a conveyor system for delivering ammunition between a loading station adjacent a storage compartment and a station for use the combination of a first endless band conveyor having a delivery end adjacent the station for use, a second endless band conveyor having a loading end

at the loading station, said conveyors being arranged in substantially end to end relation, a flame-proof casing surrounding the first conveyor, transfer means for transferring ammunition from the second conveyor to the first conveyor comprising a rotatable cylinder having an ammunition receiving recess arranged to receive a piece of ammunition from the second conveyor and upon rotation through a predetermined angle about an axis generally parallel to line of movement of the conveyors to deliver the piece of ammunition to the first conveyor and means for operating said cylinder in timed relation to the operation of a conveyor.

6. In a conveyor system for delivering ammunition between a loading station adjacent a storage compartment and a station for use the combination of conveyor means comprising a plurality of endless band conveyors arranged in substantially end to end relation and extending between said stations, ammunition transfer means at the adjacent ends of said conveyors, means for driving the conveyors simultaneously through a predetermined cycle of operation and control means for the driving means effective to initiate operation of the conveyors only when a piece of ammunition has been loaded onto each conveyor band at the loading end thereof and any ammunition brought to the delivery end of each conveyor has been removed.

7. In a conveyor system for delivering ammunition between a loading station adjacent a storage compartment and a station for use the combination of conveyor means comprising a plurality of endless band conveyors arranged in substantially end to end relation and extending between said stations, ammunition transfer means at the adjacent ends of said conveyors, means for driving the conveyors simultaneously and the transfer means through a predetermined cycle of operation and control means for the driving means effective to initiate operation of the conveyors only when a piece of ammunition has been loaded onto each conveyor band at the loading end thereof and any ammunition brought to the delivery end of each conveyor has been removed.

8. In a conveyor system for delivering ammunition between a loading station adjacent a storage compartment and a station for use the combination of conveyor means comprising a plurality of endless band conveyors arranged in substantially end to end relation and extending between said stations, means for driving the conveyors simultaneously through a predetermined cycle of operation and control means for the driving means effective to initiate operation of the conveyors only when a piece of ammunition has been loaded onto each conveyor band at the loading end thereof and any ammunition brought to the delivery end of each conveyor has been removed.

9. In a conveyor for delivering articles between two stations the combination of a pair of endless band conveyors arranged in substantially end to end relation, means forming a flame-proof wall between one of said conveyors and one of said stations, said wall having an opening between the adjacent ends of said conveyors, and means associated with said opening for transferring articles therethrough comprising a rotatable cylinder having an article receiving recess arranged to receive an article from one conveyor and upon rotation through a predetermined angle about an axis generally parallel to line of movement of

the conveyors to deliver the article to the other conveyor.

10. In a conveyor for delivering articles between two stations the combination of a pair of endless band conveyors arranged in substantially end to end relation, means forming a flame-proof wall between one of said conveyors and one of said stations, said wall having an opening between the adjacent ends of said conveyors, means associated with said opening for transferring articles therethrough comprising a rotatable cylinder having an article receiving recess arranged to receive an article from one conveyor and upon rotation through a predetermined angle about an axis generally parallel to line of movement of the conveyors to deliver the article to the other conveyor, and ejector means for moving an article between one conveyor and the recess.

11. In a conveyor for delivering articles between two stations the combination of a pair of endless band conveyors arranged in substantially end to end relation, means forming a flame-proof wall between one of said conveyors and one of said stations, said wall having an opening between the adjacent ends of said conveyors, means associated with said opening for transferring articles therethrough comprising a rotatable cylinder having an article receiving recess arranged to receive an article from one conveyor and upon rotation through a predetermined angle about an axis generally parallel to line of movement of the conveyors to deliver the article to the other conveyor, and ejector means for moving an article between one conveyor and the recess, and means for operating the ejector means in timed relation to the operation of the conveyor.

12. In a conveyor for delivering articles between two stations the combination of a pair of endless band conveyors arranged in substantially end to end relation, means forming a flame-proof wall between one of said conveyors and one of said stations, said wall having an opening between the adjacent ends of said conveyors, means associated with said opening for transferring articles therethrough comprising a rotatable cylinder having an article receiving recess arranged to receive an article from one conveyor and upon rotation through a predetermined angle about an axis generally parallel to line of movement of the conveyors to deliver the article to the other conveyor, and means for operating the cylinder in timed relation to the operation of the conveyor.

13. In a conveyor for delivering articles between two stations the combination of a pair of endless band conveyors arranged in substantially end to end relation, means forming a flame-proof wall between one of said conveyors and one of said stations, said wall having an opening between the adjacent ends of said conveyors, means associated with said opening for transferring articles therethrough from one conveyor to the other and cooperating with said opening to maintain a flame-proof seal between said stations at all times, driving means for operating both conveyors and the transfer means in timed relation, and means for controlling operation of the driving means operable to initiate operation thereof only when an article has been placed on the loading end of one conveyor band, and any article delivered has been removed from the other conveyor band.

14. In a conveyor for delivering articles between two stations the combination of a pair of endless band conveyors arranged in substantially end to end relation, means forming a flame-proof

wall between one of said conveyors and one of said stations, said wall having an opening between the adjacent ends of said conveyors, means associated with said opening for transferring articles therethrough from one conveyor to the other and cooperating with said opening to maintain a flame-proof seal between said stations at all times, driving means for operating both conveyors and the transfer means in timed relation, and means for controlling operation of the driving means and effective to prevent operation of the conveyors in the event of failure of the transfer mechanism to properly transfer an article from one conveyor to the other.

15. In a conveyor system for delivering ammunition aboard a war vessel from a magazine below the armor deck to a gun above the armor deck the combination of an endless band conveyor having a delivery end adjacent the gun, a second conveyor having a loading end adjacent the magazine, a flame-proof casing surrounding the first conveyor and transfer means adjacent and below the armor deck and above the magazine for transferring ammunition from the second conveyor to the first and cooperating with said casing to maintain a flame-proof seal between the magazine and the space above the armor deck at all times.

16. In a conveyor system for delivering ammunition between a loading station adjacent a storage compartment and a station for use the combination of a first conveyor having a delivery end

adjacent the station for use, a second conveyor having a loading end at the loading station, driving means for the conveyors, means for controlling the driving means and responsive to the loading and unloading of the conveyor for initiating a cycle of operation of the driving means, a flame-proof casing surrounding the first conveyor and transfer means for transferring ammunition from the second conveyor to the first conveyor and cooperating with said casing to maintain a flame-proof seal between the loading station and the station for use at all times.

17. In a conveyor system for delivering ammunition between a loading station adjacent a storage compartment and a station for use the combination of a first conveyor having a delivery end adjacent the station for use, a second conveyor having a loading end at the loading station, driving means for the conveyors, means for controlling the driving means and responsive to the loading and unloading of the conveyor for initiating a cycle of operation of the driving means, a flame-proof casing surrounding the first conveyor, transfer means for transferring ammunition from the second conveyor to the first conveyor and cooperating with said casing to maintain a flame-proof seal between the loading station and the station for use at all times, and driving means for operating both conveyors and the transfer means in timed relation.

RALPH L. TWEEDALE.
